LEG ELEVATOR FOR OPERATING CHAIRS

Filed Sept. 28, 1937

FIG 2

Morgan W. Baker
INVENTOR,

BY

W. B. Harman
ATTORNEY.

UNITED STATES PATENT OFFICE

2,151,729

LEG ELEVATOR FOR OPERATING CHAIRS

Morgan W. Baker, Youngstown, Ohio

Application September 28, 1937, Serial No. 166,129

2 Claims. (Cl. 155—28)

This invention relates to a leg elevator designed primarily for dental operating chairs.

The principal object of this invention is the provision of an attachment for an operating chair so designed that it will conveniently raise the legs of a patient in the event of the patient's fainting, thus placing the patient in a reclining position and allowing the blood to flow to the brain to end the fainting spell.

10 A further object of the invention is the provision of a leg elevating attachment for operating chairs, so designed and positioned on the chair that in order to elevate the feet of a patient it is only necessary to push downwardly upon the 15 handle of the elevator.

A further object of the invention is the provision of a leg elevator attachment for operating chairs, so designed as to form an attractive addition thereto.

20 A further object of the invention is the provision of a leg elevator attachment for operating chairs which is of light construction and easy to operate.

Patients in operating chairs frequently faint, thus making it necessary for the operator to relieve the fainting condition. A practical means of ending the faint is by placing the head of the patient at a lower level than the remainder of the body so that the blood may more readily flow to the brain. An operating chair is equipped with a foot rest at a substantially lower level than the rest of the chair, and there is no provision in the majority of these operating chairs for elevating this foot rest. I have provided a convenient attachment for an operating chair which will elevate the feet and legs of a patient.

35 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

40 The invention is illustrated in the accompanying drawing, wherein:

Figure 1 is a side elevation of an operating chair with my leg elevating attachment positioned thereon.

50 Figure 2 is a detail view of the leg elevating attachment in an elevating position, the relative position of the operating chair being shown in dotted lines.

By referring to the drawing it will be seen that 55 an operating chair, comprising a base 1, a seat portion 2, a back 3, arms 4, and a foot rest 5, has

been provided with a leg elevator 6. This elevator 6 is preferably formed of a crescent shaped section of tubular material having a down-turned lower end formed thereon and slidably positioned on one side of the operating chair by means of brackets 7 placed to conform with the crescent shape of the elevator. The down-turned lower end 8 of the leg elevator 6 is provided with a rubber covered roll 9 positioned at right angles thereto and of substantially the same width as the 10 operating chair. The upper end of the leg elevator 6 is provided with a handle portion 10, so designed that it may be folded up out of the way when not in use.

By referring to Figure 2 of the drawing it will 15 be seen that the leg elevator has been placed in an elevated position where it is held by means of a catch mechanism 11 formed on one of the brackets 7. A plurality of notches 12 have been provided in the body of the elevator 6. It will be 20 seen that when the leg elevator is in this position, the chair has been adjusted to a reclining position. It is obvious that any patient in the operating chair will now be in a reclining position with their head at a substantially lower level than the remainder of the body, thus causing the blood to 25 flow more readily to the brain and relieve a fainting condition.

The leg elevator may be either attached to the operating chair as an accessory thereto, or may 30 be provided for at the time the chair is constructed by the formation of the brackets 7 as an integral part of the chair itself.

What I claim is:

1. A leg elevator for operating chairs, said 35 elevator comprising a crescent shaped section of tubular material slidably maintained in brackets attached to the said operating chair and having a down-turned lower end formed thereon, a rubber covered roller of the same width as the said chair 40 positioned on one end of the said elevator and at right angles thereto together with handle portion formed on the opposite end of said elevator.

2. A leg elevator for operating chairs, said 45 elevator comprising a crescent shaped section of tubular material slideably maintained in brackets attached to the said operating chair and having a down-turned lower end formed thereon, a rubber covered roller of the same width as the said chair positioned on one end of the said elevator and at right angles thereto, together with handle portion 50 formed on the opposite end of said elevator, a catch mechanism formed on one of said brackets and a plurality of notches formed in the elevator and adapted to function therewith.

MORGAN W. BAKER.
